UNITED STATES PATENT OFFICE.

ANGELO JOSLER, OF CHICAGO, ILLINOIS, ASSIGNOR OF ONE-HALF TO FRANKLIN P. SMITH, OF CHICAGO, ILLINOIS.

WINDOW-GUARD.

1,279,747.

Specification of Letters Patent. Patented Sept. 24, 1918.

Application filed May 1, 1916. Serial No. 94,600.

To all whom it may concern:

Be it known that I, ANGELO JOSLER, a citizen of the United States, and a resident of Chicago, county of Cook, and State of Illinois, have invented certain new and useful Improvements in Window-Guards, of which the following is declared to be a full, clear, and exact description.

This invention relates to window guards, and its principal objects are to provide a guard which may be easily and quickly locked in place on a window frame or removed from a locked position thereon; to provide for adjustment for various heights and widths of windows within given limits, and to simplify and otherwise improve upon the construction of window guards. The invention consists therefore, in the several novel features hereinafter fully set forth and claimed.

The invention is clearly illustrated in the accompanying drawings in which:

Figure 1, is a front view of a fragment of a window with a simple form of the present invention applied thereto; Fig. 2, is a horizontal section taken on line 2—2 of Fig. 1; Fig. 3, is a vertical section taken on line 3—3 of Fig. 1, but showing the guard in the act of being removed from its support; Fig. 4, is a vertical section taken on the same line but showing the guard in place and the lower sash partly raised; Fig. 5, is a perspective view of a fragment of the window frame and sash showing a certain locking member for the guard; Fig. 6 is a detail, horizontal section taken on line 6—6 of Fig. 1; Fig. 7, is a detail, vertical section taken on line 7—7 of Fig. 6; Fig. 8, is a fragmental front view of a slightly modified form of the invention; Fig. 9, is a vertical section taken on line 9—9 of Fig. 8; Fig. 10 is a vertical section taken on line 10—10 of Fig. 8; Fig. 11, is a horizontal section taken on line 11—11, of Fig. 8, and Fig. 12, is a front elevation of a fragment of a window sash.

Referring to said drawings, and first to Figs. 1 to 7, inclusive, the reference numeral 12, designates the side members of a window frame; 13, the sill; 14, the upper sash and 15, the lower sash, which are slid-

ably mounted in the window frame in the usual and well known manner.

The window guard comprises an open work removable guard proper 16, and its supports 17, which are fastened to the side members 12, of the window frame by screws or otherwise. Said supports are shown as comprising upright channel iron bars 18, which extend from a point above the top of the lower sash (when closed) to a point near its bottom; on the lower end of each bar 18, is an outstanding hook 19, which, if desired, may comprise a separate piece of metal riveted or otherwise permanently secured to the bar.

At the upper end of each bar 18, is a rocking lock member 20, which is pivotally secured to the bar by a rivet or other pivotal connection 21. A short bar 22, spaced from the bar 18, by two blocks 23, 24, stands at the side of each lock member 20, and prevents side play of the latter. The bar 22, blocks 23, 24, and bar 18, are riveted or otherwise rigidly secured together.

Each lock member 20, comprises an upstanding stem portion 25, through which the pivot pin extends, a notched hook like front portion 26, the forward edge of which is curved and inclined (see Figs. 5 and 7) and a tail piece 27, which is capable of extending over the top of the lower sash when in its unlocked position, and also is capable of standing in front of an upright member of the lower sash when the latter is partly raised; the block 23, serves as a stop against which the tail piece strikes when the lock member is rocked forward (See Fig. 5.)

The window guard proper 16, may comprise any suitable grille or open work construction, and in its simplest form I have shown it as comprising upright intermediate members 28, upright end members 30, and horizontal members 29, which may be united at their intersections by rivets or by welding the members together as may be found desirable. Said upright and horizontal members may consist of flat bars or otherwise and the frame thus formed is of a size to cover the major portion of the space occupied by the lower sash.

The upright end member 30, of the guard

proper, engage with the lock members 20, and the hooks 19, and are thereby secured to the window frame as will be hereafter set forth. Said end members are preferably 5 secured to the main body of the guard proper in an adjustable manner, whereby the same guard may be adjusted to accommodate windows of various widths. This adjustable connection may comprise yoke 10 shaped members 31, one secured to each upright end bar 30, as by rivets or by being welded thereto, and the horizontal arms 32, of said members 31, slide in brackets 33, that are riveted or otherwise secured to the 15 upright end bars 28. The vertical bars of the members 31, have clips 33^a, secured thereto as by screws, 34, the end portions of which clips lie on the side of the horizontal bars 29, opposite to the upright bars of the 20 members 31, so as to slidably connect them therewith. By tightening the screws 34, the main grille or guard 16, and extension are rigidly secured together.

For the purposes of vertical adjustment, 25 the bars 30, may be provided with notches or slots 35, 36, for the reception of the hooks 19, and lock members 20. There may be one slot 35, at the top of each bar 30, and one at the bottom thereof, but I have shown the 30 several slots at both ends arranged one above the other for the purpose of vertical adjustment of the guard to accommodate window openings of various heights. In use the upper edge of a slot 36 in each bar 30, 35 rests on a hook 19, directly behind the bill thereof, whereby the guard is supported, and each lock member 20, overhangs the lower edge of a slot 35, in each bar 30, with its bill in front of the bar. When the lower 40 sash is partly raised, it stands immediately behind the tail piece 27, of each lock member (see Figs. 4, 5 and 7), thereby preventing movement of the lock members toward the lower sash. Consequently since the bills 45 of the lock members lie in front of the bars 30, the latter cannot be moved forward to disengage them from the lock members, said bars cannot be raised because the lower edges of the slots 35 will strike against the 50 undersides of the portions 26, of the hook members and as the latter cannot move upward or toward the sash, the bars cannot be raised to disengage them from the hooks 19, or lock members 20.

55 To detach the guard from its support and lock members, the lower sash is first closed; the guard is then raised, thereby swinging the lock members toward the sash, after which those parts of the bars 30, immediately below the slots 35, in which the lock members 20, are located, enter the notches in the portions 26, of the lock members and this movement of the bars 30, into the notches in the lock members permits of 55 their disengagement, at their lower ends,

with the hooks 19, whereupon the lower end of the guard may be moved backward toward the person, to free the guard from the hooks 19, after which it may be lowered and disengaged from the lock members. 70

To replace the guard, the lower ends of the bars 30, are placed upon the hooks 19, and the upper end swung toward the lower sash and into locking engagement with the lock members. It is to be observed that in 75 striking the locking members, the end bars swing them upward and backward until the bars, or the notches therein, pass by the hook portions 26, whereupon the locking members fall forward and downward under 80 the influence of gravity and lock the guard in place, the hook portions dropping in front of the bars.

In the modified form illustrated in Figs. 8 to 11 inclusive, the horizontal arms 32^a, of the extension members, 31^a, are bent back at their ends as shown in Fig. 11, and riveted to upright flat bars 32^b, in place of being secured directly to the end bars 30. The flat bars 32^b, are adjustably secured to 90 the end bars 30^a, by screws 32^c, whereby the body portion of the guard may be raised or lowered with respect to the end bars 30^a. A plurality of screw holes 32^d, are provided in the bar 32^b, to afford the vertical adjust- 95 ment of the body portion of the guard.

In place of the slots 35, 36, shown in Fig. 1, notches 35^a, 36^a, are provided at the upper and lower ends of said bars which notches are arranged for the reception of 100 the lock members 19^a, and hook members 20^a, respectively. In other respects, the construction is substantially the same as that shown in the other form of the invention.

To provide for an extra wide range of 105 adjustment, without leaving too large gaps between the end upright members 28, and the bars 30^a, additional filling in bars 28^a, may be employed which may be attached to the member 31^a, of the guard proper if so 110 desired. As here shown, the bar 29^a, is attached to the upright bar 32^b, by a screw 32^e, the head of which is covered by the bar 30^a, to prevent unauthorized removal and the free end of said bar 29, is seated in the clip 115 33^a, which is fastened to the upright bar of the member 31^a. The bars 28^a, 29^a, may be riveted together and the ends of the upright bar 28^a, may be secured to the horizontal portions 32^a, of said member 31^a, by 120 screws 32. This extra filling in section will be provided wherever it is necessary to expand the guard horizontally to accommodate a very wide window.

In some cases, the upper ends of the side 125 members of the lower sash are carried above the upper meeting rail as shown in Fig. 12, and in such cases an opening or hole 15^a, may be formed in each of said projecting end portions for the reception of the tail 130

pieces of the lock member, or as an alternative, a block may be secured to the extension to provide a flat end on the sash.

I am aware that there are other alterations and modifications of the invention later displayed without departing from the spirit of this invention. I desire, therefore, not to limit myself to the exact forms of construction shown and described, but intend in the following claims to point out all of the invention disclosed herein.

I claim as new and desire to secure by Letters Patent:

1. A window guard, comprising an open work guard proper having upright end bars, hook members supported on the side members of a window frame and arranged for engagement with the lower ends of said bars, and lock members pivotally supported on 20 said members of the window frame and having hooklike portions overhanging the upper ends of said bars and arranged to prevent upward and lateral movement of the guard proper, said locking members having tail 25 portions formed integral therewith and arranged to stand in front of the lower sash of a window frame to thereby lock the guard proper to said window frame, but capable of movement across the plane of the lower sash, 30 when the latter is fully lowered, whereby the guard proper may be detached from said lock members and hook members by an upward movement of the guard.

2. A window guard, comprising an open work guard proper, supports arranged to be secured to the window frame, and adapted to detachably support the guard proper, gravity acting locking members for the upper end of the guard proper pivotally secured to the window frame, each of said locking members comprising a unitary structure having a guard retaining hook adapted to automatically engage said guard proper in locking position whenever said 45 guard proper is placed on its supports and moved into place on the window frame, and having a tail piece which moves over the lower sash when the locking member is moved to unlocked position, and which 50 stands in front thereof when the locking member is in locking position.

3. A window guard comprising an open work guard proper, members adapted to be carried by the window frame for detachably 55 securing the lower end of the guard proper to the window frame, and locking members pivotally carried by the window frame, for locking the upper end of the guard proper to the window frame, said locking members 60 being arranged to automatically assume a locking position, each of said locking members comprising a unitary structure having a portion adapted to overhang and depend in front of a portion of the guard proper, and 65 thereby lock the same against upward and

lateral movement, and having also a tail portion arranged to stand in front of the lower sash when in locked position, but capable of movement transversely of said sash when the latter is fully lowered, whereby 70 the locking member may be swung out of locking engagement with said guard proper.

4. A window guard, comprising a guard proper, supports therefor adapted to be carried by a window frame, and locking members for the upper end of said guard proper adapted to be pivotally carried by said window frame, and arranged to automatically assume their locking position, each of said locking members comprising a unitary structure having a guard retaining hooklike portion adapted to overhang a portion of the guard proper and prevent upward and lateral movement of the guard, and having also a tail piece arranged to stand in front of the lower sash when in locking position but capable of movement transverse of said sash when the latter is fully lowered whereby the locking member may be swung back out of locking position. 80

5. A window guard, comprising a guard proper, supports therefor adapted to be carried by a window frame, and locking members for the upper end of the guard proper, adapted to be pivotally carried by said window frame, each of said locking members having a hooklike portion adapted to engage the side of the guard proper when in locked position to prevent lateral movement thereof and having also a tail piece adapted to stand in front of the lower sash when in locked position but capable of being moved over said sash when the latter is fully lowered, to release the guard proper, each of said locking members having upwardly extending 90 notches adapted to receive adjacent portions of the guard proper when the latter is moved upward to disengage it from its lower fastening means. 95

6. A window guard, comprising a pair of upright supporting bars arranged to be secured to a window frame, supporting members secured to the lower ends thereof, locking members, one pivotally secured on each bar and movable in a direction transverse of the sash and acting automatically to assume their locking position, each locking member comprising a unitary structure having a hooklike guard engaging portion at one end and a tail portion at the other end which is adapted to stand in front of the lower sash but capable of movement over the same when the latter is fully lowered, and an open work guard proper adapted to be detachably secured on said supports and movable into 115 locked condition with said locking members when said sash is fully lowered. 120

7. A window guard, comprising upright supporting bars arranged to be secured to a window frame, supporting members secured 130

- to the lower ends of said bars and sash controlled locking members secured to the upper ends of said bars and acting automatically to assume their locking position, a guard proper 5 having upright end bars arranged for locking engagement with said supports and locking members, said end bars being provided with adjustment means whereby the body portion of the guard proper may be raised or 10 lowered with respect to said supports and locking members to accommodate windows of various heights.
8. A window guard, comprising upright supporting bars arranged to be secured to a 15 window frame, supporting members secured to the lower ends of said bars and sash controlled locking members secured to the upper ends of said bars, a guard proper having upright end bars arranged for locking engagement with said supports and locking members, said upright end bars and body of 20 the guard proper being adjustably secured together, whereby the body portion may occupy various positions of adjustment relative to the locking members.
9. A window guard, comprising a pair of supports and sash controlled locking members arranged to be carried by a window frame, a guard proper having a main open 25 work body portion arranged to cover the major portion of the lower sash opening and end extensions slidably secured to the main portion, said extensions being arranged for locking engagement with said supports and locking members.
10. A window guard, comprising a pair of supports and sash controlled locking members arranged to be carried by a window frame, a guard proper having a main open 30 work body portion arranged to cover the major portion of the lower sash opening and yoke shaped end extension members, slidably secured thereon, and upright end bars secured thereto, said upright end bars 35 being arranged for locking engagement with said supports and locking members.
11. A window guard, comprising a pair of supports and locking members arranged to be carried by a window frame, a guard proper having a main body portion and yoke shaped extension members, slidably secured thereon, upright end bars secured thereto, and having notches for the reception of said supports and locking members, and supplemental filling in bars removably secured to 45 said end upright bar and yoke shaped extension members.
12. A window guard, comprising a guard proper, guard supporting members, arranged to be secured to the window frame, and guard locking members pivotally supported by said window frame adjacent the top of the lower sash, each locking member being constructed and arranged to automatici-

callly engage the guard proper in locking position when the guard proper is inserted in place on its supports, said lower sash and locking means forming the sole means for preventing lateral and upward movement of the guard.

13. A window guard, comprising a guard proper, guard supporting members arranged to be secured to the window frame and guard locking members, pivotally supported on said window frame adjacent the top of the lower sash, and each having a tail piece adapted for engagement with said lower sash, and having also a hook like front portion for securing the guard proper in place against upward and inward movement, said hook like portion lying in the path of movement of said guard proper when the latter is placed in its locked position, whereby said locking members are automatically brought into locking engagement with said guard proper, said lower sash and locking means forming the sole means for preventing lateral and upward movement of the guard.

14. A window guard, comprising an open work guard proper, supporting members therefor, arranged to be secured to a window frame, locking members pivotally supported by the window frame adjacent the top of the lower sash, and having tail members arranged to engage said sash, said locking members having also hook like front portions for locking engagement with the guard proper, the front edges of said hook like portions being inclined and lying in the path of the closing movement of the guard proper when inserted in place before a window whereby the locking members automatically lock the guard to the window frame, said lower sash and locking means forming the sole means for preventing lateral and upward movement of the guard.

15. A window guard, comprising an open-work guard, supports therefor engaging the lower end of the guard, said supports being secured to the side members of a window frame, and locking members pivotally supported in said side members of the window frame, and each having a hook portion arranged to lockingly engage with said guard to prevent lateral and upward movement thereof, and a tail piece projecting toward the lower sash of the window and adapted to engage the sash, when raised, to thereby prevent movement of the locking member to unlocking position, but capable of being moved over said sash, when fully lowered, to unlock the guard from said locking member.

16. A window guard comprising a guard, supports therefor engaging the lower end of the guard, said supports being secured to the side members of the window frame, locking members pivotally supported in said side

members of the window frame, and having hook portions arranged to lockingly engage with said guard and tail pieces which extend back and engage the lower sash, when 5 raised, but which are arranged to be moved back over the lower sash, when fully low- ered, the pivotal connections for said locking members being at their lower ends whereby they tend to tilt downward by gravity and stops for limiting downward tilting 10 of the locking members.

ANGELO JOSLER.
